(57) **CLAIM**

The ornamental design for a bat, as shown and described.

DESCRIPTION

FIG. 1 is a side view of a bat, the opposite side view of the bat being the same.

FIG. 2 is the same side view of the bat as FIG. 1 with the addition of a reference circle;

FIG. 3 is an end view of the bat of FIG. 1.

FIG. 4 is another end view of the bat from FIG. 1, from the opposite end shown in FIG. 3; and,

FIG. 5 is a detailed side view of the reference circle disclosed on FIG. 2.

The dashed lines indicate unclaimed portions and unclaimed surface ornamentation of the bat that forms no part of the claimed design. The dash-dot-dash lines show unclaimed boundaries that form no part of the claimed design.
